Primary Examiner — S. Bryan Reinholdt, Jr.*(74) Attorney, Agent, or Firm* — Fei Hung Yang(57) **CLAIM**

The ornamental design for a drinking straw, as shown and described.

DESCRIPTION

FIG. 1 is a perspective view of a drinking straw, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines represent inner portions for the drinking straw, that form no part of the claimed design.

1 Claim, 4 Drawing Sheets(56)
